UNITED STATES PATENT OFFICE.

SEBASTIANO PARISI, OF NEW YORK, N. Y.

INNER SOLE.

1,402,375.

Specification of Letters Patent.

Patented Jan. 3, 1922.

Application filed January 22, 1921. Serial No. 439,130.

To all whom it may concern:

Be it known that I, SEBASTIANO PARISI, a citizen of Italy, and residing at New York, in the county of New York and State of New York, have invented certain new and useful Improvements in Inner Soles, of which the following is a specification, such as will enable those skilled in the art to which it appertains to make and use the same.

This invention relates to inner soles and particularly to devices of this class designed to be connected directly with the foot of the wearer, and the object of the invention is to provide an inner sole with means for holding the toes of a foot in proper position when the foot is placed within a shoe and also to hold the toes of the foot in proper position when the wearer of such inner sole is walking, running or standing still thus preventing the overlapping of the separate toes of a foot as is usually the result, especially when shoes of too narrow widths are used; and with this and other objects in view the invention consists in an inner sole of the class specified, constructed and operated as hereinafter described and claimed.

The invention forming the subject-matter of this application is an improvement on that described and claimed in U. S. patent granted to me August 10, 1920, No. 1,349,095 and is fully disclosed in the following specification, of which the accompanying drawing forms a part, in which the separate parts of my improvement are designated by suitable reference characters in each of the views, and in which:

Fig. 1 is a longitudinal sectional view through a shoe showing my improved inner sole mounted therein and indicating the method of its use;

Fig. 2 a plan view of the toe portion of the inner sole shown in Fig. 1 detached;

Fig. 3 a bottom plan view of the toe portion of the sole as shown in Fig. 2;

Fig. 4 a partial section on the line 4—4 of Fig. 2 and on an enlarged scale;

Fig. 5 a bottom plan view of the heel portion of the inner sole and with part of the construction removed and showing certain details of the sole construction.

Fig. 6 a view similar to Fig. 2 but showing a slight modification; and,

Fig. 7 a partial section on the line 7—7 of Fig. 5 and on an enlarged scale.

In the practice of my invention I provide an inner sole 10 which is preferably composed of a main central body portion 11 of leather, the side edge portions of which are reduced as indicated at 12 in Fig. 7 of the drawing, and channeled strips of felt or similar material 13 are passed over the reduced portions 12 and secured thereto by two lines of stitching 14, and this construction produces a strong and finished edge for the sole or the body portion 11 thereof. The top and bottom faces of the sole are also covered by sheets of fabric 15 and 16 also preferably composed of felt.

The heel and central portion of the sole 70 is cut longitudinally and transversely as shown at 17 and 18 in Fig. 5 of the drawing for the purpose of making the central or body portion of the sole as well as the heel portion thereof flexible, whereby in the use 75 of the inner sole the same will conform to the foot of the wearer and also to the shoe and permit the free action of the foot within the shoe in walking, jumping, running or the like.

The toe portion of the sole is provided with a plurality of elongated and spaced apertures 19, 20, 21 and 22 which are arranged in the manner illustrated in Fig. 2 of the drawing, and mounted in these apertures 85 are reinforcing strips 23, the parts thereof which extend into the apertures 19 being beveled as indicated at 24, and the outer or flanged portions 25 thereof overlap the bottom face of the sole and said strips are 90 secured in position by tacks or similar devices 26 passed into the body portion 11 of the sole. A plurality of elongated bars 27 are adapted to be mounted in the apertures 19 to 22 inclusive and said bars are triangular in form in cross section and serve to 95 secure a toe strap member 28 in position as hereinafter set out.

The strap member 28 is secured to one side edge portion of the sole as indicated at 29 100 and, in the form of construction shown, this strap member is divided longitudinally as shown at 30 into three comparatively narrow straps 31, 32 and 33. The strap 33 is longer than the strap 32, and the strap 32 is longer 105 than the strap 31, and the separate straps are joined as shown at 34 adjacent to the attached end 29 thereof. The strap member 28, or the separate straps thereof are adapted to be passed upwardly and downwardly through 110

the apertures 19 to 22 to form toe loop members 35, 36, 37 and 38 thereof in the manner illustrated in Fig. 4. The downwardly directed looped portions 39 are secured within the 5 apertures 19 to 22 inclusive by the wedge bars 27 as clearly shown in Fig. 4. It will be seen on a consideration of Figs. 2 and 3 of the drawing that all of the straps 31, 32 and 33 combine to form the top loop 35, while the 10 straps 32 and 33 combine to form the toe loop 36, and the top loops 37 and 38 are formed by the strap 33 alone in the construction shown in Figs. 2 and 3 of the drawing.

I also employ a supplemental and narrow 15 strap member 40 which is secured to the opposite side edge of the sole as shown at 41, and the end portion thereof is passed downwardly and upwardly through the aperture 22, and secured therein to form another toe 20 loop 42, as clearly shown in Figs. 2 and 4 of the drawing.

In my prior patent which is hereinbefore referred to, I employ a single and comparatively wide strap member, which is passed 25 transversely of the toe portion of the sole and formed into a plurality of toe loop members in the same manner as the formation of the loop members 35 to 38 inclusive, but I find that by providing a strap member composed of a plurality of comparatively narrow straps formed into toe loop members approximately, as indicated in the accompanying drawing, I produce a far better and more effective sole of the class and for the purpose 30 specified, and by reason of the fact that the tension or pull on the separate straps 31, 32 and 33 to properly fit the foot of a wearer may be taken up and thus the separate toes of a foot may be brought in proper position, 35 or in a position which will be comfortable to the wearer and yet effectively produce the desired result.

It will be apparent that I am not necessarily limited to any particular arrangement 40 of the separate straps or strap members employed, nor to the detail construction of said strap members or straps, and in Fig. 6 of the drawing I have shown a slight modification in which the strap 33 of the strap member 28 45 terminates in a loop member 37 and substituted for the supplemental strap 40 is another supplemental strap member 43 which is composed of separate straps 44 and 45, the strap 44 being shorter than the strap 45 and 50 fashioned to form part of the toe loop 42, the other strap 45 forming the other part of said toe loop and also forming the toe loop 38 by passing said last named strap downwardly and upwardly through the apertures 22 and 60 21 respectively. It will also be understood that I am not necessarily limited to the specific means herein shown and described for securing the strap members or straps in position to form the separate loop member, and

various changes in and modifications of the 65 construction herein shown and described may be made, within the scope of the appended claims, without departing from the spirit of my invention or sacrificing its advantages.

Having fully described my invention, 70 what I claim as new and desire to secure by Letters Patent, is:—

1. An inner sole the toe portion of which is provided with a plurality of independent straps, and means for securing said straps 75 in connection with the sole to form a plurality of toe loops in connection therewith.

2. An inner sole the toe portion of which is provided with a plurality of independently adjustable toe loops into which the 80 toes of the foot are adapted to pass, said toe loops being formed by a plurality of straps.

3. An inner sole of the class described the toe portion of which is provided with a plurality of toe loops into which the separate 85 toes of the foot are adapted to pass, said toe loops being formed by a plurality of straps.

4. An inner sole of the class described the toe portion of which is provided with a plurality of toe loops into which the separate toes of the foot are adapted to pass, said toe loops being formed by a plurality of straps, and means in the toe portion of the sole for adjusting said straps so as to form 90 toe loops of different sizes and for holding said loops in position.

5. An inner sole of the class described comprising toe and heel parts, a strap member secured to one side of the toe part, means 100 on the toe part of said sole in connection with which said strap member operates to form a plurality of toe loops of said strap, and said strap member being composed of a plurality of independently adjustable straps. 105

6. An inner sole of the class described comprising toe and heel parts, a strap member secured to one side of the toe part, means 110 on the toe part of said sole in connection with which said strap member operates to form a plurality of toe loops of said strap, said strap member being composed of a plurality of independently adjustable straps, and a strap member secured to the other side edge of the toe part of the sole and co-operating 115 with said first named means to form one or more toe loops in connection with said sole.

7. An inner sole of the class described comprising toe and heel parts, a strap member secured to one side of the toe part, means 120 on the toe part of said sole in connection with which said strap member operates to form a plurality of toe loops of said strap, said strap member being composed of a plurality of independently adjustable straps, a strap member secured to the other side edge 125 of the toe part of the sole and co-operating

with said first named means to form one or more toe loops in connection with said sole, and means for securing all of said toe loops in position.

5 8. An inner sole of the class described comprising toe and heel parts, the body portion of the sole being composed of leather, the edge portions of which are provided with soft fabric edgings, means for 10 permitting of the free movement of the heel and central portion of the sole, fibrous facings for the top and bottom faces of the sole, and the toe part of the sole being provided with a plurality of adjustable strap 15 members adapted to form a plurality of adjustable toe loop members thereon.

9. An inner sole of the class described comprising toe and heel parts, the toe part being provided with a plurality of elongated 20 and spaced apertures, a strap member secured to one side of the toe part and composed of a plurality of independent straps said straps being adapted to be passed downwardly and upwardly through the apertures 25 of said toe part, and means in said apertures

and cooperating with said straps for securing said straps in said apertures in different positions of adjustment.

10. An inner sole of the class described comprising toe and heel parts, the toe part 30 being provided with a plurality of elongated and spaced apertures, a strap member secured to one side of the toe part and composed of a plurality of independent straps, 35 said straps being adapted to be passed downwardly and upwardly through the apertures in said toe part, means in said apertures and cooperating with said straps for securing said straps in said apertures in different positions of adjustment, and metallic reinforcing members secured to said sole and extending into said apertures. 40

In testimony that I claim the foregoing as my invention I have signed my name in presence of the subscribing witnesses this 20th day of January, 1921.

SEBASTIANO PARISI.
